UNITED STATES PATENT OFFICE.

DAVID L. GALLUP, OF SOUTH BEND, INDIANA, ASSIGNOR TO BENDIX BRAKE COMPANY, OF CHICAGO, ILLINOIS, A CORPORATION OF ILLINOIS.

ROLLING APPARATUS.

Application filed March 29, 1926. Serial No. 98,108.

- This invention relates to apparatus for rolling the lining of arcuate brake shoes, preferably yieldingly by arranging a heavy spring to urge the roller against the lining. 5 In one very desirable arrangement, the roller is carried by a lever arm fulcrumed at the center of the arc of the shoe, and the shoe is supported at its ends and at an intermediate point. I prefer to arrange the parts 10 so that they may be adjusted relatively to the fulcrum of the lever arm, to permit rolling shoes curved on arcs of different radii,—i. e. shoes of different sizes.

The above and other objects and features 15 of the invention will be apparent from the following description of one illustrative embodiment shown in the accompanying drawing, in which:

Fig. 1 is a top plan view of the apparatus, 20 with a brake shoe shown in position in dotted lines;

Fig. 2 is a section through the apparatus on the line 2—2 of Fig. 1; and

Fig. 3 is a detail section on the line 3—3 25 of Fig. 1.

The illustrated apparatus is intended for rolling the lining 10 of an arcuate brake shoe 12, which shoe is fully described in Patent No. 1,567,716, granted Bendix Brake 30 Company Dec. 29, 1925, on an application filed by Adiel Y. Dodge. The apparatus may include, or be mounted on, any suitable bed or base 14.

One end of the shoe is supported by a pin 35 16, which may be inserted in any one of three holes 18, and which may be threaded or not as desired. The pin is formed with a collar 20, the top of which forms a shoulder supporting the lower one of the two arms 40 forming the fork at the end of the shoe.

The opposite end of the shoe engages an abutment 22 having a ledge 24 on which the side of the end of the shoe rests. Abutment 22 is held by a pin 26 (threaded if desired) 45 insertible into any one of three (or more) openings 28, and by a similar pin 30 insertible in any one of three (or more) openings 32.

If the shoe is too long to rely on its 50 own rigidity against springing, it may additionally be supported at an intermediate point by one or more pins 34, the one shown being carried by abutment 22 and being arranged to engage the inner edge of the web. 55 The shoe may also be supported by one or

more pins 36, engaging the bottom of the web of the shoe, to prevent tipping. This pin may be inserted in any one of several openings 38.

The lining is rolled down by a roller 40, 60 shown journalled in a U-shaped carrier 42, and having the ends of its spindle 44 projecting through guide slots 46 in a member 48 which, with a handle 50 of any desired length, forms a level arm, fulcrumed on a 65 pin 52 at the center of the arc of the brake shoe. Roller 40 is urged against the lining by a heavy coil spring 54 sleeved on a stem 56 carried by carrier 42.

Member 48 has several openings 58, for 70 the fulcrum part 60 mounting the lever arm on pin 52, to permit lengthening the lever arm for shoes of different sizes. Openings 18, 28, 32, 38, and 58, in the particular embodiment illustrated, permit rolling the linings of shoes for brakes 12, 14, and 16 inches in diameter.

It is important to note that running the roller off either end of the lining, and then back on again, effectively breaks down the 80 ends of the lining against the flattened spaces provided for the end rivets, to guard against the ends of the lining curling up and dragging against the brake drum. If the ends of the lining were on the same arc as the rest, 85 the ends beyond the last rivets would tend to project away from the shoe at tangents. By riveting against flattened spaces, and then breaking down the lining with the roller, this is effectively prevented. 90

While one illustrative embodiment has been described in detail, it is not my intention to limit the scope of the invention to that particular embodiment, or otherwise than by the terms of the appended claims. 95

I claim:

1. Apparatus for rolling the linings of arcuate brake shoes comprising, in combination, an abutment for one end of the shoe, a fixed pivot to support the other end of the shoe, a support adapted to engage an intermediate part of the web on the inner side of the shoe, a roller adapted to engage the lining on the outside of the shoe, a lever arm carrying the roller and fulcrumed at the center of the arc of the shoe, and a spring for urging the roller against the shoe. 100

2. Apparatus as defined by claim 1, in which the various parts may be adjusted relatively to the fulcrum of the lever arm. 110

to permit rolling the linings of shoes having radii of different lengths.

3. Apparatus for rolling the linings of arcuate brake shoes comprising, in combination, an abutment for one end of the shoe, a fixed pivot to support the other end of the shoe, a roller adapted to engage the lining on the outside of the shoe, a lever arm

carrying the roller and fulcrumed at the center of the arc of the shoe, and a spring for urging the roller against the shoe and toward said center.

In testimony whereof, I have hereunto signed my name.

DAVID L. GALLUP.
